COLLAPSIBLE TUBELIKE CONTAINER FOR
PASTES

Leopold Rado, Whitehaven, England

Application September 12, 1946, Serial No. 696,385
In Great Britain September 19, 1945

9 Claims. (CL. 222—94)

1

The present invention relates to improvements in collapsible tube-like containers for pastes which are provided with an outlet to expel portions of the contents by applying pressure on the tube wall.

An object of the present invention is to provide a collapsible tube-like container having an elastic outlet through which portions of the contents can be expelled and after each expulsion the elastic outlet thereby seals itself automatically.

Another object of the present invention is to provide a collapsible tube-like container preferably made entirely from a pliable elastic non-metallic material of thermo-plastic nature, for example a vinyl resin, particularly polyvinyl chloride with a high content of plasticiser in which container the packed liquids or pastes are placed between two welded ends of a tubing, and an aperture is provided proximate one of the ends thereof.

A still further object of the present invention is to provide a tube-like container having one end of which is of a neck like formation and an aperture for expelling portions of the contents is provided proximate one end of the neck portion thereof and whereby the contents may be expelled only when the neck portion is bent in a direction opposite to that of the aperture and pressure applied to the tube walls.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a front elevational view of an improved collapsible tube-like container constructed in accordance with the present invention.

Figure 2 is a side elevational view of Figure 1 shown in a manner of employment.

Figure 3 is a modified form of Figure 1 wherein three neck portions and a flap portion are provided.

Figure 4 is a further modified form of Figure 1 wherein four neck portions are provided of a zig-zag character.

Figure 5 is a side elevational view of a further modified form of Figure 1 showing a single neck structure with a flap having a fringed portion.

Figure 6 is a fragmentary perspective view of a modification of Figure 1 with parts broken away and parts shown in section.

Figure 7 is a perspective view of a modified form of Figure 1 is illustrated

2

form of collapsible tube-like container showing the upper portion thereof.

Referring more particularly to the drawings, Figures 1 and 2 illustrate a collapsible tube-like container constructed in accordance with the present invention wherein a container body of a pliable elastic non-metallic material of thermo-plastic nature, generally designated at 11, one end of such container being welded as at 12 and the other end being welded as at 12a. It will be noted that a neck portion 13 is formed at the end portion 12a, such neck portion 13 being provided with an aperture 14.

It will be noted from Figure 2 that the neck portion 13 does not rise from a flat base but is welded about its medial portion and provides neck shaped housings at both sides of the weld. The aperture 14 in the neck 13 is made at right angles to the longitudinal length of the neck 13 and such aperture or slit is not to exceed one half of the circumference of said neck. Apertures or slits 14 may be provided at both sides of the neck portion as desired. Such may be the case when the expulsion of the contents will occur only from that aperture opposite to that direction in which the neck is bent.

The container body 11 may be filled with any desirable liquid or paste like material 15 and may be emitted from the tube only when the neck portion thereof is bent as shown in Figure 2. Referring more particularly to Figures 3 and 4 there is illustrated a modified form of construction of the present invention wherein a plurality of neck portions 13a having apertures 14a is provided. Also a flap portion 12b is provided for aiding the rigidity of the neck portions 13a and which may incidentally act as an applicator for applying the contents of the tube 11a to the desired surface area. In Figure 4 the neck portions 13b are of a zig-zag construction. It will also be noted that a filling eyelet 16 is provided on the side of the tube 11b for replenishing of the substance within the tube 11. The plurality of neck portions aid materially in distribution of a predetermined amount of substance over an area governed by the width of the flap 12c, whereas with the one neck form it may be desired to cover only a small area when only one pass over the same would be necessary, however, it may be desired to cover a greater area with only one pass of the tube over such area. It is with this in mind that applicant has provided the plurality of neck portions.

Referring more particularly to Figure 5, a further modified form of Figure 1 is illustrated

wherein the flap portion 12^d covers the entire width of the upper portion of the tube 11^c and is provided with a fringed flap portion 17 which aids in the application of the substance from the aperture 14^c in the neck portion 13^c.

A further modified form of Figure 1 is shown in Figure 6 wherein a partition or wall 18 extends longitudinally of the tube 11^c in such a way that two dissimilar substances may be carried within the one tube and that an aperture 14^d may be applied to either side of the neck portion 13^d for expelling the desired contents by bending the neck portion 13^d of the tube in a direction opposite to that of the desired aperture.

In Figure 7 a modified form of the invention is shown wherein a bendable neck 13^e is attached to the tube body 11^e. A cap 21 is provided to protect the neck from being bent during transport.

It will be noted more particularly that the basic concept of the invention common to all forms of the invention herein disclosed and described is the provision of a longitudinally extended narrow neck portion at the top of the tube wherein the neck portion 13 is narrower than the width of the tube 11 and that such neck portion has been formed by a pressing and drawing action whereby the medial portion of the same is under great elastic strain thereby tending to afford extreme rigidity to the neck to resist any bending movement thereof. An aperture 14 or any suitable opening may be made in this neck portion. Under some conditions it is preferable to make such opening in the form of a slit whereby the longitudinal axis of such slit is at right angles to the longitudinal dimension of the neck and whereby upon bending the neck in a direction opposite to the side of the tube wherein the slit is made the contents 15 of the tube may be expelled by applying pressure about the walls of the tube 11. The foregoing is more fully shown and will be more completely understood when read in connection with Figures 1 and 2.

While I have disclosed herein the best form of the invention known to me at the present time, I desire it to be understood that I reserve the right to make changes and modifications in the herein described embodiment of the invention provided such changes fall within the scope of the following claims.

What I claim is:

1. A collapsible tube-like container for pastes, the neck of which is provided with a self-sealing aperture for permitting expulsion of the contents therethrough by application of pressure on the tube wall, wherein the tube neck is bendable and the aperture is made in the side wall thereof, through which aperture the contents are expelled by applying pressure on the tube wall and at the same time bending the neck in opposite direction to the aperture.

2. A collapsible tube-like container for pastes

as claimed in claim 1 wherein the body and neck are of an elastic material.

3. A collapsible tube-like container as claimed in claim 1 wherein the aperture is a slit across the neck which slit is less than one-half the circumference of the neck.

4. A collapsible tube-like container as claimed in claim 1 wherein the tube is provided with a partition longitudinally therethrough and wherein apertures are provided at opposite sides of the neck whereby the contents of the tube on one side of the partition may be expelled by one aperture and the contents on the other side of said partition by the other aperture.

5. A collapsible tube-like container as claimed in claim 1 wherein a welded flap surrounds the neck.

6. A collapsible tube-like container as claimed in claim 1 wherein the container is provided with a plurality of necks.

7. A collapsible tube-like container as claimed in claim 1 wherein the container is provided with a plurality of necks of zig-zag formation.

8. For use with a collapsible tube-like container an improved neck-like end receivable on said tube-like container, a slit in the side wall of said neck transversely thereof, the length of which is less than one-half of the circumference of said neck, said neck being elastic and bendable for emitting the contents of said container upon the simultaneous application of pressure on the side walls of the container and the bending of the neck in a direction opposite to the slit.

9. A collapsible container for pastes comprising a container body, and a container neck communicating with the body and bendable with respect thereto, said neck having a self-sealing aperture made in a side wall of said neck openable for expulsion of the contents of the container on application of pressure to the container body wall and simultaneous bending of the neck along a line coinciding with the aperture and opposite to the aperture.
